METHOD OF KNITTING

Eugene St. Pierre, Pawtucket, R. I., assignor to
 Hemphill Company, Pawtucket, R. I., a corporation of Massachusetts

Application October 31, 1951, Serial No. 254,129

1 Claim. (Cl. 66—8)

1

This invention relates to the art of knitting hosiery on circular, independent needle, knitting machines. A primary object is to improve upon present methods of producing hosiery in a wide variety of properly proportioned sizes.

It is the custom of manufacturers of hosiery, especially of infants', children's and misses' anklets, to offer the trade a so-called "line" of stockings varying in sizes from, say, four to eleven, but otherwise identical with respect to character and weight of yarns employed, fineness of fabric, etc.

Uniformity of fabric is obtained by knitting all sizes upon machines having the same number of needles per inch of cylinder circumference. The desired lengths of the various parts of the stockings are obtained by knitting the desired number of courses in each. For slight changes in size, of the order of one or two sizes, no change in circumferential proportions is required as a rule but, for a wider range of sizes, variations in circumferential proportions are essential.

To obtain anything but the most minor alterations in the circumferential dimensions and, at the same time, retain all of the characteristics of the fabric, it has been assumed by the hosiery industry that a change in the diameter of the needle cylinder is required, together with an increase or decrease in the number of needles so that the same number per inch of cylinder circumference results and, consequently, the number of loops per inch of fabric remains constant regardless of cylinder size. This belief resulted from or led to the assumption that, to obtain uniform fabric in the various stocking sizes, it was essential that the operative relation between needles and sinkers must be always the same.

As an example of this prior art practice, the following up to date schedule of a representative manufacturer is submitted:

Stocking Size	Cylinder Diameter	Number of Needles in Cylinder
Inches		
4-5½	2	130
6-6½	2½	144
7-7½	2½	160
8-8½	2½	180
9-9½	3	200
10-10½	3½	220

From the machine manufacturers' viewpoint, such a multiplicity of machines for the production of a single type of hosiery is most objectionable. Each change in cylinder size involves an extensive and costly redesign. The tooling required for production costs many thousands of dollars in each instance and production itself is complicated in no small degree by the fact that,

while all of the machines are similar, many of the parts are in fact different and require different adjustments, since the problems encountered in the operation of a very small size are more numerous and different than those relating to the larger sizes. Also, parts inventories must be much larger.

From the user's point of view, experience has shown that, unless he can offer all of the standard sizes of a given line, he can not sell his product. Because of this, he has to gamble upon the business he is likely to receive for the various sizes and proportion his machine purchases accordingly. The demand for different sizes fluctuates periodically so that the user frequently finds himself with too many machines of one size and too few of another with the result that, if he is to meet the market demands, he must purchase additional machines which he may not need a few months later and see some of his machines of other sizes standing idle. In addition, he must carry in stock spare parts for all sizes.

To avoid the complications resulting from so many cylinder sizes is the problem solved by this invention. It was realized that the controlling factors of identity of fabric are identity of yarn and uniformity of loop structure. It was also realized that circumferential dimensions depended upon the number of loops per course. From this, it followed that different sizes would require a different number of needles.

Since a cylinder of one diameter was to be used, if possible, it became evident that the needle spacing would vary with the number of needles employed so that the travel of the needles in relation to the sinkers would have to vary also so as to draw, in all cases, the equal lengths of yarn required for equal loop structure. Thus, the problem was solved. It will be noted that this solution is opposed in almost every respect to prevailing practice and beliefs.

As just stated, if the size of cylinder, the yarn and the loop structure of the stitches are constant throughout, a stocking having more stitches per course than another will be circumferentially larger but, aside from length, which is determined by other factors, will be otherwise identical. This is illustrated in the accompanying drawing, of which:

Fig. 1 is a representation of two anklets scaled to the relative proportions of sizes 11 and 5, respectively; and,

Figs. 2, 3 and 4 are diagrammatic illustrations for the purpose of explaining how equal yarn lengths are drawn by the needles in cylinders of a given diameter in which the needle spacing varies.

In the embodiment which will be described, the invention is practiced upon machinery of 3-inch

cylinder diameter. Contrary to present belief, this permits production of a full "line" of sizes from, say, four to eleven, each having fabric so identical that corresponding portions of stockings of different sizes as they come from the machine cannot be readily distinguished from each other or from other similar commercial "lines" in this respect.

Assuming that a 3" cylinder is to be used throughout, the smaller sizes such, for example, as 4-5½ may be produced by means of 130 needles, whereas such sizes as 10-11½ or thereabouts may be produced upon the same size cylinder equipped with 200 needles. Since 130 needles equally spaced upon a 3" cylinder will be spaced apart quite a little further than 200 needles and since the same loop structure is required to obtain the same fabric from each, the same length of yarn must be drawn by each of the 200 needles as by each of the 130 needles. This means, of course, that the travel of the needles will be so adjusted that, in the 130 needle case, their downward travel terminates at a higher point with respect to the drawing edge of the sinkers than in the 200 needle instance, as shown in Fig. 2 as compared with Fig. 4 which, in an illustrative sense, indicates the difference between the two.

The objective is the same as the practice which has been followed by the knitting industry; i. e., to obtain the same length of yarn in each loop regardless of stocking size and thus obtain substantial identity of fabric characteristics in all sizes. However, instead of obtaining this uniformity of loop length by means of uniform needle spacing in cylinders of different sizes and uniform motion of needles with respect to the sinkers, it is obtained by varying the number of needles in conformity with the desired circumferential proportions of the stocking, spacing these needles evenly apart by corresponding different amounts and obtaining uniformity of loop length and the consequent identity of fabric by varying the motion of the needles in relation to the sinkers so that equal length of yarn per loop will nevertheless be drawn.

Intermediate sizes between those specifically mentioned above may be obtained in the same way by equipping the cylinder with a suitable number of needles without changing its size, assumed to be 3", and by manipulating the needles as described above so as to draw the same length of yarn per loop as before and as illustrated, for example, in Fig. 3.

In fact, if desired, the schedule set forth above may be followed exactly with respect to the number of needles and the same sizes obtained; the only variation being that the cylinder diameter remains constant as compared with the six different cylinder sizes shown in the schedule.

It will now be evident that this improved method of producing a wide range of sizes of hose having uniform fabric reduces the problems of cost involved in the design, manufacture, and use of the number of machines of different cylinder diameters previously considered necessary by the trade. It simplifies the training of knitters and fixers, and lessens the inventory in individual mills. It also permits hosiery mills to equip themselves with machines which are readily and inexpensively convertible from the manufacture of one size to another, thereby enabling them to follow production trends without the necessity of purchasing new machines for one size while serviceable machines of another size stand idle.

In addition to the above advantages, the pres-

ent inventor has overcome another problem of the knitting industry, hitherto considered insoluble. It is still impossible to produce a dial and cylinder machine having a dial of less than 2¾" in diameter. Consequently, since it has been thought by the trade that smaller dials were necessary for the smaller sizes of stockings it has been assumed that these sizes could not be made automatically on dial-rib machines; consequently, they have been made on plain machines and separately made tops hand transferred thereto by a separate operation.

No such difficulty is encountered with a dial and cylinder machine having a 3" cylinder, for example; and, by this invention, the size range of such machines has been materially extended since the so-called complete "line" can be made by following exactly the same procedure disclosed above for all sizes.

20 The applicant is aware that different numbers of needles have been used before in a cylinder of one diameter but they have never been used for the objective of this invention. The purpose has been to change the gauge of the hosiery knit to ac-

25 commodate auxiliary equipment, such as transfer rings, already in the possession of a customer, etc. To vary the number of needles in cylinders of one diameter and to obtain a wide range of sizes otherwise having identical fabric characteristics by adjusting the stitch length so that equal amounts of yarn will be drawn in all instances, is new and directly opposed to heretofore accepted assumptions.

30 Wherever the word "identical" is used in this application with respect to fabric or fabric characteristics, microscopic identity is not meant, but only such similarity as would satisfy average commercial standards.

35 The expression "substantial range of sizes" is meant to include not only the range given in the comparative table herein but any fraction of that table which is greater than that which has hitherto been produced with commercial perfection on a given cylinder having a given number of needles.

40 I claim:

A method of knitting on circular, independent needle, knitting machinery, a substantial range of hosiery sizes having identical fabric characteristics in different circumferential dimensions, 45 wherein knitting is effected by means of cylinders of constant diameter using numerically different complements of needles in different cylinders to produce said different circumferences of fabric, wherein the needles of said numerically different complements are evenly spaced apart by correspondingly different amounts, and wherein the same amount of yarn per loop is drawn by the needles in corresponding parts of said hosiery of different circumferential dimensions.
